UNITED STATES PATENT OFFICE.

CHARLES GIBSON, OF NORTHAM, ENGLAND.

FLAGSTAFF FOR GOLF-LINKS AND THE LIKE.

1,135,372.

Specification of Letters Patent. Patented Apr. 13, 1915.

Application filed March 27, 1914. Serial No. 827,547.

To all whom it may concern:

Be it known that I, CHARLES GIBSON, golf-club maker, a subject of the King of Great Britain, of Westward Ho Golf Club, 5 Northam, in the county of Devon, England, have invented new and useful Improvements in or Relating to Flag-Staffs for Golf-Links and the like; and I do hereby declare that the following is a full, clear, 10 and exact description of the invention such as will enable others skilled in the art to which it appertains to make and use the same.

The invention comprises certain improvements in and relating to flag-staffs for golf links and the like of the type in which the flag-staff is mounted upon a spring controlled fitting adapted to work on a spiked metal rod which is inserted in the ground.

These devices have only partially served the purpose intended, and the object of the invention is to prevent in a more efficient manner, the enlargement of the hole in the ground in which the spiked end of the metal rod is inserted, which may be occasioned by the abnormal wind pressure against the flag staff or by sheep pressing against the same, or anything else which may cause the same to lean in the direction 30 of pressure from their set position.

According to this invention the flag-staff is held in engagement with the spiked metal rod by the action of a spring held in compression by a flexible connection one end 35 being secured to the spiked rod and the other being threaded to receive a nut and washer which bears down upon the top of the spring the lower end engaging with projections formed on the flag-staff member, 40 thereby firmly retaining it in a normally upright position with respect to the spiked rod and having means whereby the tension of the spring may be adjusted according to whether a long or short staff is intended 45 to be used.

In order that my invention may be fully understood I will now proceed to describe the same with reference to the accompanying drawings in which:

Figure 1 is a view of the complete device partly in section. Fig. 2 is an enlarged

view of same. Fig. 3 is a view showing the flexible connection secured to the spiked rod and the means employed for adjusting the tension of the spring. Fig. 4 is a device to be hereinafter referred to.

The spiked rod 10 is provided at its upper end with an enlarged portion or flange 11 upon which is adapted to rest the hollow tube or casing 12 and prevented from lateral movement thereon by a circular projection 13. Centrally disposed on said projection is a ring or the like 14 to which is attached a flexible connection 15, the upper portion of which engages with an eye or hook 16 formed on the threaded rod or spindle 17.

The hollow tube or casing 12 is provided internally near its lower end with two or more projecting pieces 18 which serve to retain the spring 19 said spring being held in compression thereon by a nut and washer working on the threaded rod or spindle 17 thereby allowing the tension of same to be adjusted as desired by a suitable key or the like 20.

The upper end of the casing 12 is threaded or otherwise formed so as to engage with the flag or other staff 21 which staff is provided with a recess 22 to enable it to clear the upper end of the threaded spindle 17.

What I do claim as my invention and desire to secure by Letters Patent is:—

1. A tension device for flag-staffs comprising a pair of members having adjacent ends disposed in abutting relation, one of said members being tubular and the abutting end of the other member being entirely closed, yieldable means constantly tending to draw adjacent ends into engagement, and a projection on the closed end of the last named member extending a predetermined distance into the tubular member to prevent bodily lateral movement thereof and permitting same to tilt laterally against the influence of said yieldable means.

2. A tension device for flag-staffs comprising a pair of members having adjacent ends disposed in abutting relation, one of said members being tubular and the abutting end of the other member being entirely closed, a spring within the tubular member

having the end thereof adjacent the other member in engagement with a fixed portion of the tubular member, a follower element engaging the other end of the spring, and 5 a ring link loosely connected with the follower element and with the member having the closed abutting end.

In testimony whereof I have signed my name to this specification in the presence of two subscribing witnesses.

CHARLES GIBSON.
